(57) **CLAIM**

The ornamental design for diffusing evaporator of active substances, as shown and described.

DESCRIPTION

FIG. 1 is a front perspective view of a diffusing evaporator of active substances, showing our new design;

FIG. 2 is a front elevation view thereof;

FIG. 3 is a side elevation view thereof, taken from the left of FIG. 2;

FIG. 4 is a top plan view thereof;

FIG. 5 is a side elevation view thereof, taken from the right of FIG. 2; and,

FIG. 6 is a bottom plan view thereof.
